UNITED STATES PATENT OFFICE.

EDWARD R. GRAMS, OF ROSEGLEN, NORTH DAKOTA.

MOUNTING FOR THRESHING-MACHINES.

No. 910,528.

Specification of Letters Patent.

Patented Jan. 26, 1909.

Application filed January 17, 1908. Serial No. 411,368.

To all whom it may concern:

Be it known that I, EDWARD R. GRAMS, citizen of the United States, residing at Roseglen, in the county of McLean and State 5 of North Dakota, have invented certain new and useful Improvements in Mountings for Threshing-Machines, of which the following is a specification.

It is well known that threshing machines 10 and the like are subject to detrimental vibration and jar when traveling over rough roads, but they are not usually provided with springs to compensate for such vibration since it is obviously not desirable to have the 15 machine rest on springs while in operation.

The object of this invention is an improved mounting designed to be interposed between the body portion and the running gear of a threshing machine and which is arranged to 20 form a resilient or rigid connection therebetween according as desired.

With this and other objects in view that will more fully appear as the description proceeds, the invention consists in certain constructions and arrangements of the parts that I shall hereinafter fully describe and then point out the novel features thereof in the appended claims.

For a full understanding of the invention 30 and the merits thereof, reference is to be had to the following description and the accompanying drawing, in which:

Figure 1 is a side elevation of my improved spring mounting, with parts in section. Fig. 35 2 is a detail view in perspective of the extensible brace. Fig. 3 is a detail view in section of the ratchet and pawl; and, Fig. 4 is a similar view of one end of the axle showing a modified form thereof.

40 Corresponding and like parts are referred to in the following description and indicated in all the views of the drawing by the same reference characters.

Referring to the drawing, A and A' designate 45 respectively the two lower and upper side sills of the main supporting frame of a threshing machine, and B the rear axle to both ends of which my improved mountings are applied.

50 Each of my improved mountings comprises two guide members 1 secured at their upper ends to a lower sill A and extending downwardly therefrom and spaced from each other as shown to form a channel in which 55 the corresponding end of the rear axle B is mounted for vertical movement. The lower

ends of the guide members 1 travel freely through openings 2 formed in the ends of a bracket 3 which is secured to the lower side of the axle B and which extends forwardly 60 and rearwardly therefrom. Two expansion springs 4 are interposed between the respective ends of the bracket 3 and such lower sill A and form a resilient connection between the axle and the body portion of the machine, 65 whereby the axle is permitted to ride upwardly in the channel when it receives a jolt, and is thus prevented from transmitting the latter to the body portion.

An extensible brace 5 is secured to the axle 70 B and comprises a lower actuating screw 6 pivotally mounted at its lower end between two ears 7 provided on the upper side of the axle B, an oppositely threaded upper actuating screw 8, and a turnbuckle 9 having its 75 ends oppositely threaded and in engagement with the respective actuating screws 6 and 8. The upper end of the screw 8 is preferably flattened as indicated at 10 and normally travels freely through a bearing strap 11 secured to the adjacent upper sill A¹, a screw clamp 12 being mounted in said bearing and being adapted to hold the flattened end 10 rigidly in the bearing and to the body portion. The turnbuckle 9 is provided with a 80 ratchet 13 and a handle 14 that has a reversible pawl 15 operatively engaging with the said ratchet and rendering the handle capable of rotating the turnbuckle in either direction, which movement obviously results in 85 the extension or contraction of the brace.

In the practical use of my improved mountings when it is desired to dispense with the use of the springs and to establish a rigid connection between the body portion and the 95 axle, the braces are rigidly secured at their upper ends to the body portion and are extended, which movement obviously raises the body portion and thus relieves the springs of the weight thereof and of any tension.

The above operation is reversed to reestablish the spring connection between the body portion and the running gear. It will be further noted that the extensible braces may be employed to quickly and easily adjust the body portion to level it when the threshing machine is operating on uneven ground.

While my improved mounting has been described in connection with threshing machines, it is to be understood that it is applicable to vehicles generally.

It is to be understood, that if desired the guide members 1 may travel in vertical channels 16 formed at the opposite sides of the axle as clearly shown in Fig. 4, instead of in 5 openings in the ends of the bracket 3.

Having thus described the invention, what I claim is:

1. The combination with the axle and body portion of a vehicle, of means for establishing a resilient connection therebetween, 10 an extensible brace secured to one of said parts and having a sliding connection at its other end with the other part, and means for rigidly connecting said last named end of the brace to the corresponding part, whereby to hold the resilient means inoperative.
2. The combination with the axle and body portion of a vehicle, of springs interposed therebetween and arranged to support 20 the body portion, a brace rigidly secured at one end to one of said parts and having a sliding connection at its other end with the other part, means for rigidly connecting said other end of the brace to the corresponding 25 part, and means for extending the brace, as and for the purpose specified.
3. The combination with the axle and body portion of a vehicle, of springs interposed therebetween and arranged to sustain

the body portion, a brace rigidly secured at 30 one end to one of said parts and having a sliding connection at its other end with the other part, means for rigidly connecting said last named end of the brace to the corresponding part, said brace being constructed 35 in sections, and a turn buckle adjustably connecting said sections, as and for the purpose specified.

4. The combination with the axle and body portion of a vehicle, of means for establishing a resilient connection therebetween, 40 a brace rigidly secured at one end to one of said parts and having a sliding connection at its other end with the other part, means for rigidly connecting the last named end of the 45 brace and the corresponding part, said brace being constructed in sections, a turn buckle adjustably connecting said sections, and a handle mounted upon the turn buckle and having a ratchet and pawl connection there- 50 with, as and for the purpose specified.

In testimony whereof I affix my signature in presence of two witnesses.

EDWARD R. GRAMS. [L. s.]
